UNITED STATES PATENT OFFICE.

ALBERT KRAUTH, OF HAMILTON, OHIO.

AUTOGRAPHIC REGISTER.

1,142,441.

Specification of Letters Patent.

Patented June 8, 1915.

Application filed July 1, 1912. Serial No. 706,973.

To all whom it may concern:

Be it known that I, ALBERT KRAUTH, a citizen of the United States, residing at Hamilton, in the county of Butler and State of Ohio, have invented certain new and useful Improvements in Autographic Registers, of which the following is a specification.

My invention relates to an improvement in autographic registers directed primarily to paper feeding mechanism therefor, for delivering predetermined lengths within a defined movement of the crank handle, and for webbing one of the strips of paper fed, with tension means controlling the same, together with means for locking the rewound web within the machine.

One of the objects of my invention is to provide means for feeding or delivering a given length of paper within a limited movement of the manipulating mechanism therefor. This, in the preferred embodiment illustrated, is comprised of a pair of coaxing feeding rolls between which the paper is fed, with the peripheries of said rolls frictionally engaging each other, and with one of said rolls having a circumference equal to the length of strip desired to be delivered. A crank handle for rotating said rolls adapted to engage stop elements to interrupt the rotation of the crank handle to define the limits of strip feed.

Another object of my invention is to provide a record strip webbing roll with compensating mechanism interposed between the driving elements to release the drive of the record roll relatively with its increasing web diameter and winding tautness, to cause a slippage or lost action, so as not to impair the feed of the paper of the manifold strips traversing in a registry operation.

Another object of my invention is to provide compensating mechanism interposed between the transmission elements connecting a record webbing roll and main paper feeding instrumentalities, comprising a pair of parallel transmission members adjacently disposed and engaged by friction elements under a yielding resistance, causing the one to slip upon the other when its transmitting power exceeds such resistance.

Another object of my invention is to provide an autographic register with a lock member adapted to engage a removable spindle, supporting a web of paper within a register, to prevent its displacement, with the lock member controlled by the position

of a register door frame, so as to lock and release simultaneously with the opening and closing of the register door frame.

The various other features of my invention will be more fully set forth in the description of the accompanying drawings, forming a part of this specification, in which:

Figure 1 is a side elevation of a register illustrating my improvements with the top forward portion thereof in sections. Fig. 2 is a section on line α , α , Fig. 1. Fig. 3 is a detailed elevation partly in section of the handle and stop abutments therefor.

1, 2 represent side frames of the register, within which the various webs of paper are supported by any well-known means, and, as illustrated, three supply webs are provided, although the number may vary, according to the particular usage to which the register is applied.

3 represents an end casing door hinged to the side frames 1, 2, and adapted to be swung outwardly. This door is provided with the usual locking instrumentalities, for locking the door in closed position, and, as illustrated, comprises a latch member 4 fixed to the rock shaft 5, with the rock shaft suitably journaled upon the door, and the latch member 4 adapted to engage with a catch 6 formed upon and projecting from the side frame.

It is usual to provide two such locking instrumentalities one adjacent to each side frame. The rock shaft 5 may be provided with an arm for mutilating or perforating the record strip, to indicate upon the record sheet each time the door has been opened.

7 represents the margin frame suitably hinged to the side frames in any well-known manner common in the art, and 8 represents a writing tablet secured to the side frames, and spanning an opening formed in the margin frame.

One of the webs of paper is usually a pre-printed strip containing a series of signatures, as for instance, sales slips of predetermined length. It has been found desirable to feed these given lengths a distance coördinately with their length to deliver the same exteriorly of the machine upon a single rotation of a crank handle or manipulating member, and this, in the preferred embodiment illustrated comprises a feeding roll 9 fixed to the shaft 10, said shaft being journaled within the side frames, with one

end thereof projecting beyond the side frames to which the crank handle 11 is fixed.

The circumference of the roll 9 is equal to the length of the slip, and defines the length of web fed or delivered upon each rotation thereof. The length can, however, be varied by either changing the diameter of the roll 9, or fractionally rotating the same, but one of the characteristics herein 10 is to provide a limit, or limits of roll rotation to insure a definite feed or length of delivery of paper at each delivery manipulation.

12 represents a companion feed roll, its 15 periphery engaging with the periphery of roll 9, and under tension therewith, to provide a gripping engagement upon the paper fed between said rolls, and insure a positive feeding action. The axle or shaft ends 20 13 of the roll 12 are each journaled in a slide block 14 slidably mounted within ways formed in the side frames 1 and 2, and each slide block is engaged by a spring 14^a, to maintain a downward pressure thereon, and 25 in consequence, a pressure upon the roll 12 against the periphery of the roll 9.

15 represents a gear fixed on shaft 10 of a pitch diameter equal to the diameter of the roll 9, with its teeth in mesh with a 30 pinion 16 fixed upon the axle 13 of the roll 12. Thus, the roll 12 is positively rotated relatively with the rotation of roll 9, causing uniformity of action on the paper. This is essential when manifold sheets are delivered to prevent one sheet from slipping upon the other as they travel between the rolls, as such would disturb the correlative alignment of the delivered sheets, the second sheet, or delivered sheets are usually the 35 duplicates of each other, and in preprinted form, and the entries on one transferred onto a second by manifolding processes common in the art.

The crank handle is interrupted in its rotation by providing a stop in its circuitous path, to randomly determine each predetermined length of feed of paper to be delivered or interval of paper advance, with the hand crank released by movement counter to the circuitous feeding movement for a second operation, and this is accomplished as follows:—17 represents a stop plug projecting from the side frame 1 adapted to engage or be engaged by a lug 19 projecting from the slide bar 18 forming a part of the crank handle 11, and slidably mounted therein, said lug being adapted to engage with the lug 17 in one position, and released therefrom by a movement radiating 50 from the axis of the crank handle 11, and, as illustrated, by a downward movement, to carry the lug 19 away from the rigid stop member 17.

The slide rod 18 is mounted under tension 55 within the crank handle to direct the same

toward the crank handle axis and this is comprised by providing an extension 20 to the slide rod 18 having a collar 21 on the end thereof, and 22 represents a collar secured within the crank handle 11, and 70 through which the extension 20 passes, and 23 represents a spring engaging the collars 21, 22.

24 represents a hand hold fixed to the slide rod 18. Thus, it will be seen that in order 75 to release the crank handle for a feeding operation, the handle 24, its slide rod 18 must be moved downward away from the crank handle axis, releasing the engagement between the stop members 17, 19, affording clearance for the crank handle, and enabling a complete rotation to be made.

To prevent the operator from maintaining a releasing pressure on the handle 24, while manipulating the same, during a feeding operation, which, if undisturbed, would permit the lug 19 to be held beyond its stop engagement, I provide a cam lug 25 opposite the stop plug 17 and directed toward a limit of the handle circuit, which cam lug is 80 adapted to engage the lug 19 of the crank handle at its limit of releasing position, and direct the same compulsory toward the crank handle axis, to bring the lug 19 in 85 plane with the stop lug 17, to compel engagement therewith.

It is obvious that the crank handle could be provided with a series of interruptions to define limits of paper feed, as if the predetermined lengths or intervals of advance 100 of the paper in lengths equal multiples of the circumference of the main feeding roll 9, or other divisions thereof, which would not disturb the alignment of the strips with the margin frame, or in any way interfere with 105 the complete issuance of each slip comprised in the web as a unit, and it is further obvious that manipulating mechanism for rotating the feeding rolls may be utilized, functioning to produce the same results 110 without departing from the features of my invention.

In the form of register illustrated, three supply webs are provided, two of which are delivered exterior of the machine, while the 115 third comprises a record strip rewound within the register. This strip may be advanced to a length equal to the lengths of strips or slips delivered, recording an entire entry, or the same may be advanced to a lesser degree functioning as a summary record. The uses of registers under both classes are 120 well-known and common in the art.

In winding the paper upon a roll to web 125 the same, the diameter thereof constantly increases, and as this roll receives its motion through transmission mechanism connected with the main power elements, a pulling action is produced disturbing the relative travel or feed of the sheets or strips. There- 130

fore, to prevent undue pulling strains or advancement of the strip beyond that produced by the main feeding rolls, I provide compensating mechanism for relieving said 5 roll of such undue drive or pulling strain to permit a slipping action in the transmitting instrumentalities of the record roll, without interfering with the winding or compactness of web.

10 26 represents a spindle, preferably of square form carrying a webbing roll or core 27, which in practice is provided with suitable means, not shown, for securing the paper to the periphery in the initial use to 15 properly start the winding action for the web. The spindle 26 is preferably square, so that the parts can be readily keyed thereto, and at the same time permit convenient removal of the spindle to withdraw the lock 20 from the machine.

25 28 represents a gear in mesh with gear 15 of the main feeding rolls, said gear 28 is loosely journaled upon a stud pin 29 fixed to the side frame, and 30 represents a companion gear to 28, and adjacent to the same, with each of said gears provided on opposing sides with an annular groove adapted 30 to receive the leather washers 31, 32, respectively, having friction clutch characteristics to clamp the gears together.

35 33 represents a spring engaging the gear 30, and a housing plate 34, to exert tension against said gear to frictionally clamp the washers together. The tension of the spring governs the degree of resistance at which the washers will be maintained in a driving 40 relation, and if the drive required exceeds such resistance, it will cause slippage between the members causing the record spindle 26 to remain stationary.

45 35 represents a gear fixed on the spindle 26 in mesh with gear 30, completing the train of gears from shaft 10 to the spindle 26. Such operation may be further explained by assuming that the operator is commencing to web a record strip, in which instance, the speed of rotation of the roll or core 27 may exceed the speed of the feeding rolls 9 and 12, and if the record webbing rotation were 50 constant it would result in a pulley strain of the paper between the feeding rolls destroying the accurate function of the feeding rolls. After a period of use the diameter of the record web is materially increased and 55 its circumferential length exceeds that of the feeding length of a single feeding cycle of the feeding rolls, consequently the drive must be disconnected from the record web to prevent paper-pulling strains from such 60 source. The connecting resistance of the drive is such as to always insure the winding of the record web to a proper degree of tautness.

65 While I have illustrated the compensating mechanism as interposed between the

driving train of gearing, it is obvious that the same could be in direct engagement with the spindle or core, without departing from the features of my invention, in fact, various modifications are readily inherent 70 from the disclosures herein, and I therefore do not wish to be limited other than specifically set forth in the claims.

To release the peripheral engagement between the main feeding rolls 9 and 12, I 75 provide a bell crank lever 36 pivotally mounted upon the shaft 10, with one arm of the lever adapted to engage the axis of the roll 12, and move the same upwardly to provide a clearance between said two rolls, 80 in which position the paper can be conveniently adjusted. As shown, a bell crank lever 36 is provided at each end of the roll.

37 represents a rock shaft provided with pins adapted to engage an arm of a bell 85 crank lever 36 to control its movement.

38 represents a ratchet wheel fixed to the shaft 10, and 39 represents a pawl pivoted to the side frame 2 engaging with said ratchet wheel, to prevent retrograde movement of the feeding mechanism or rolls. 90

The spindle 26 is removably secured within the side frames for withdrawal of the record web, and therefore, to prevent displacement of the gear 35, it is provided with 95 hub extensions journaled within the side frame 2 and housing plate. To remove the spindle, it is necessary to open the casing door 3, and this prevents accidental or malicious interference with the functioning of 100 said roll.

40 40 represents a lever having a yoke extension 41 adapted to engage into an annular groove 42 formed in the spindle 26, preventing lateral movement of the spindle when the lever 40 is engaged therewith. The free end of the lever engages a cam lug 43 projecting from the door 3, with the lever 40 maintained under tension by a spring 44 in a direction toward the door. Thus upon 110 opening the door the lever 40 will swing toward the door, releasing its engagement with the spindle, and upon closing the door, the lever is moved simultaneously therewith to its locking position. The lever 40 is provided with a lip 45 projecting through a notch formed in the side frame, and engaging over the exterior surface of the side frame, thereby preventing displacement of the lever 40 or tampering with the same to 115 120 effect an unauthorized release of the spindle 26.

Having described my invention, I claim:—

1. In an autographic register, paper feeding mechanism, rotative propelling mechanism therefor, a spindle for webbing a length of paper advanced by said feeding mechanism, a series of gears in train connecting said spindle and propelling mechanism, two of said series of gears in parallelism and 125 130

coaxially journaled, each having annular opposing grooves, friction rings inserted in each of said grooves to frictionally contact with each other, and tension means for yieldingly urging one of said gears toward the second.

2. In an autographic register, a frame, paper feeding mechanism, rotative propelling mechanism therefor, a spindle removably journaled in said frame for webbing a length of paper advanced by said feeding mechanism, a series of gears in train connecting said spindle and paper feeding mechanism with the gear of the train connected with the spindle confined within the frame coaxially with the spindle and removably engaged therewith.

3. In an autographic register, a frame, paper feeding mechanism, rotative propelling mechanism therefor, a spindle removably journaled in said frame for webbing a length of paper advanced by said feeding mechanism, a series of gears in train connecting said spindle and paper feeding mechanism with the gear of the train connected with the spindle confined within the frame coaxially with the spindle and removably engaged therewith, and two of the gears of the series in parallelism and coaxially journaled and frictionally engaged and yieldingly separable to relieve the spindle of rotative movement under abnormal webbing strains.

4. In an autographic register, a pair of coaxing feed rolls, one of said rolls being of a circumference equal to an interval length of paper to be fed upon each rotation of said roll, a pair of intermeshing gears rotatively connecting said rolls, each gear of a fixed diameter equal to the diameter of the roll, to which it is respectively connected, a spindle removably journaled in said frame for webbing a length of paper advanced by

the feeding mechanism, a series of gears in train connecting said spindle with one of 45 said feed roll gears, with one gear of the train connected with the spindle confined within the frame coaxially with the spindle and removably engaged therewith, and two of the gears of the series in parallelism and 50 coaxially journaled and frictionally engaged and yieldingly separable to relieve the spindle of rotative movement under abnormal webbing strains.

5. In an autographic register, a casing, a door thereto, a spindle mounted in the casing and adapted for endwise withdrawal from the casing, and a blade swingingly mounted engaging into an annular groove in the spindle and preventing its endwise withdrawal, the free end of said blade divided, one portion thereof engaging through an orifice in the casing to limit the movement of the blade and the second portion engaged by the closed door to hold the blade in active 65 position.

6. In an autographic register, a casing, a door thereto, a spindle mounted in the casing and adapted for endwise withdrawal from the casing, a gear for rotating said spindle 70 confined within the casing coaxially with the spindle, and a blade swingingly mounted engaging into an annular groove in the spindle and preventing its endwise withdrawal, the free end of said blade divided, 75 one portion thereof engaging through an orifice in the casing to limit the movement of the blade and the second portion engaged by the closed door to hold the blade in active position.

In testimony whereof, I have hereunto set my hand.

ALBERT KRAUTH.
